Carl Nelson, Eau Claire, Wis., assignor to National Pressure Cooker Company, Eau Claire, Wis., a corporation of Wisconsin

Application December 19, 1934, Serial No. 54,495

Term of patent 7 years

To all whom it may concern:

Be it known that I, Carl Nelson, a citizen of the United States, residing at Eau Claire, in the county of Eau Claire and State of Wisconsin, have invented a new, original, and ornamental Design for Safety Valves, of which the following is a specification, reference being had to the accompanying drawing, forming part thereof, and in which

Figure 1 is a side elevation of the safety valve; and

Figure 2 is a top view thereof.

I claim:

The ornamental design for a safety valve, as shown.

CARL NELSON.
